CLAIM

The ornamental design for a knife handle with gut hook, as shown and described.

DESCRIPTION

FIG. 1 is a left side view of the knife handle with gut hook, showing my new design;

FIG. 2 is a top elevation of the knife handle with gut hook;

FIG. 3 is a bottom elevation thereof;

FIG. 4 is a front elevation thereof; and,

FIG. 5 is a rear elevation of the knife handle with gut hook illustrated in FIGS. 1-4.

The broken line showing of a blade in FIG. 1 is for illustrative purposes only and forms no part of the claimed design.
